UNITED STATES PATENT OFFICE.

WILLIAM M. MITCHELL, OF LOUISVILLE, KENTUCKY.

ANCHOR FOR RAILWAY-RAILS.

1,235,493.

Specification of Letters Patent. Patented July 31, 1917.

Application filed May 7, 1917. Serial No. 166,875.

To all whom it may concern:

Be it known that I, WILLIAM M. MITCHELL, a citizen of the United States, and a resident of Louisville, county of Jefferson, and 5 State of Kentucky, have invented certain new and useful Improvements in Anchors for Railway-Rails, of which the following is a specification.

The invention relates to anchors for preventing the longitudinal movement or creeping of railroad rails and seeks to provide a cheap, simple form which can be securely welded to the rail.

The invention consists in the features of 15 improvement hereinafter set forth, illustrated in different preferred forms in the accompanying drawings and more particularly pointed out in the appended claims.

In the drawings Figure 1 is a plan view of 20 one form of the present invention. Fig. 2 is an end view thereof with parts shown in section. Fig. 3 is a side view of a two-way anchor embodying the present invention. Fig. 4 is an enlarged detail cross section 25 of the form shown in Fig. 3. Figs. 5 and 6 are end views of modified forms of the invention. Fig. 7 is a perspective view and Fig. 8 is a plan view of further modifications.

0 The improved anchor is preferably constructed of forged or rolled iron or steel and is of simple form comprising only a tie-abutting portion and a rail-engaging portion disposed at an angle to the tie-abutting 35 portion and arranged in part, at least, to overlap and be welded to the upper face of the rail. Preferably the rail-engaging portion is in the form of a jaw arranged to extend over both the upper and lower faces of 40 the flange of the rail and preferably the anchor has a bracing portion between the rail and tie-abutting portions.

The form shown in Figs. 1 and 2 comprises a part or member 1 which extends beneath one side of the rail base, a tie-engaging 45 abutment 2 depending from the front edge of the part 1 and a flange-engaging hook 3 extending upwardly from the outer edge of the part 1 and inwardly over the 50 base flange of the rail. Preferably, as shown, a hollow bracing rib 4 extends between the portions 1 and 2. Such an anchor could be formed from a piece of angle bar or forged from an L-shaped piece of 55 sheet iron or steel by bending one projecting portion downwardly to form the tie-engag-

ing abutment 2 and shaping the other projecting portion to form the hook 3.

This anchor can be readily secured to one of the base flanges of the rail before the latter is laid but preferably the anchors are applied when the rails are in position in the track. The anchor may be fused or welded electrically or otherwise to one of the base flanges of the rail. Preferably when applying the anchor to a rail in place in the track, the edge portion of the base flange of the rail adjacent the tie is heated nearly to the fusion point by a suitable oxy-acetylene torch. The rail anchor is applied in position with the abutment 2 engaging the tie and the parts 1 and 2 extending above and below one of the base flanges of the rail. Portions of the anchor and particularly the edge portions of the hook flange 3 are fused 75 to the adjacent portions of the rail base by aid of the welding torch. Preferably, to avoid all danger of weakening the rail, a fillet of metal fused from a suitable steel rod, is run into the corners between the base 80 flange of the rail and the edges of the hook flange 3 of the anchor, as indicated at *a*, the welded fillet being united or incorporated with the metal of the rail base and anchor. Indeed, if desired, the anchor may be 85 largely or wholly held in place by such an added fillet or fillets. Such fillets cannot be readily applied to the edges of the portions of the anchor beneath the rail base when the rail is in position in the track and for this 90 reason, the fillet *a* shown in Fig. 2, extends only to a slight extent beneath the edge of the rail base. But the anchor can be readily secured in position with sufficient rigidity by fusing or welding the overlapping 95 flange 3 thereof to the upper face of the rail base.

In the manner described, the anchor is solidly and permanently united to the rail without weakening the metal body of the 100 rail and it is not, like the anchors now in use, dependent upon a friction grip so that it cannot be dislodged by the expansion and contraction or other movements of the rail. It should also be noted that the parts 1 and 105 3 of the anchor form jaw members which snugly engage the edge of the rail base and aid in resisting the reaction thrust of the tie against the abutment 2 and, in this way, assist in resisting the strain upon the welded joint between the anchor and the rail.

The form shown in Fig. 3 is similar to

that shown in Figs. 1 and 2 except that the part 1^a thereof is of sufficient length to extend between two adjacent ties and is provided at each end with a tie-engaging abutment 2^a. In this form, 2 hook flanges 3 are preferably provided, one adjacent each of the tie-engaging abutments 2^a, and preferably also, as indicated in Fig. 4, the edge of the part 1^a between the hook flanges 3 projects outwardly to a slight extent, beyond the adjacent edge of the rail base and is solidly united thereto by a fillet 6 welded into the corner between the vertical face of the rail base and the projecting horizontal face of the part 1^a.

15 The form shown in Fig. 5 is similar to that shown in Figs. 1 and 2 except that the body portion 1^b extends entirely across beneath the base flange of the rail and is provided with a rail-engaging part, such as a hook 5, the inner dimensions of which are of such size that the anchor can be readily applied to a rail in position in the track. This form can be solidly and permanently 20 united to the rail as described or, if desired, 25 may be spot welded thereto either electrically or otherwise, as indicated at points *c*.

The form shown in Fig. 6 is preferably made of a drop forging or steel casting and 30 comprises a jaw portion 6 having a tie-engaging abutment 7 depending from its front end and an integral upwardly projecting portion 8 in the form of a fork, the members of which are provided, adjacent their 35 upper ends, with inwardly projecting bosses 9, so that the fork is adapted to suitably support a detector bar. This form constitutes a single piece, combined rail anchor and detector bar clip and is provided, as indicated, with integral bracing flanges 10. In 40 welding or fusing this form to the base of the rail, fillets are preferably fused or welded between the adjacent parts as indicated at *d*. The anchor shown in Fig. 7 is formed of a short section of an angle bar, 45 and comprises a flange or member 11, the inner portion of which is adapted to partially overlap one of the base flanges of the rail and a flange or member 12 which forms 50 a tie-engaging abutment. The inner portion of the flange 12 is cut away to admit the rail flange beneath the inner end of the flange 11. Preferably, as shown, the inner end portion of the flange 12 is bent rearwardly to form a brace 13 between the abutment 12 and the under side of the rail base. 55 This form is applied in position with the inner part of the flange or member 11 overlapping and welded to the upper face of the rail base preferably by fillets at its edges, as indicated at *e*.

The present invention may also be applied in connection with rail anchors now in use to securely lock the same in position upon 60 the rail. Such anchors usually comprise

jaws for engaging the opposite flanges of the rail base and a tie-engaging abutment. In the form shown in Fig. 8, one flange-engaging jaw 14 is formed upon the end of a cross member 15 that extends beneath the rail 70 and is provided with a tie-engaging abutment 16. The other jaw 17 and the adjacent end of the part 15 are provided with coöperating wedging shoulders 18. The wedging shoulders act, when the jaw 17 is 75 driven in position, to force the opposite jaws into snug engagement with the rail base. In this and similar types of anchors there is danger that the jaws will work loose. In accordance with the present invention, to 80 overcome this objection, after the jaw 17 is driven into a gripping position, a fillet or projection *f* is welded or fused to the base flange of the rail in engagement with the outer end of the jaw 17 to securely hold it 85 in position. Preferably also, to prevent the disengagement of the anchor in case it moves with the rail away from the tie, a second fillet or projection *f'* is welded to the rail base at a diagonally opposite corner 90 of the anchor and engages the inner end of the jaw 14 adjacent the tie. If desired, the fillets or projections *f* and *f'* may be welded to the adjacent portions of the anchor as well as to the rail. Other forms 95 of anchors now in use can be securely locked in position on the rail in this way.

It is obvious that changes may be made in the details set forth without departure from the essentials of the invention as defined in 100 the claims.

I claim as my invention:

1. In anti-creepers for railway rails, the combination with a rail, of a one-piece rail anchor comprising a depending flange arranged to abut against the side of a cross tie and a jaw embracing one only of the flanges of the rail base and held against relative movement thereon solely by a fused or welded joint, the upper and lower members 105 of said jaw coöperating to resist the strain upon said joint due to the thrust upon said tie abutting flange.

2. In anti-creepers for railway rails, the combination with a rail, of a one-piece rail anchor comprising a depending abutment 110 arranged to engage the side of a cross tie, an upper jaw member or flange overlapping and secured by a fused or welded joint to the upper face of the rail base, and a lower 115 jaw member engaging the lower face of the rail base at one side only to aid in resisting the thrust upon said joint.

3. In anti-creepers for railway rails, the combination with a rail, of a one-piece anchor comprising a jaw embracing one flange only of the rail base and fused or welded thereto, said jaw member having a depending flange arranged to abut against the side 125 of the tie.

4. In anti-creepers for railway rails, the combination of a rail and a jaw member engaging one flange only of the rail base and permanently united thereto without weakening the metal body of the rail, said jaw member having a depending tie-engaging abutment.

5. The combination with a rail and its supporting cross tie, of an anchor arranged to abut against the side of the tie and having a flange overlapping and fillet-welded at its edges to the upper face of the base flange of the rail.

6. The combination with a rail and its supporting cross tie, of an anchor having a flange overlapping and fillet-welded at its edges to the upper face of the base flange of the rail, said anchor having an integral depending abutment arranged to engage the side face of a cross tie.

7. The combination with a rail and its supporting cross tie, of an anchor arranged to abut against the cross tie and having a jaw engaging the base flange of the rail base, and a body of metal welded to the rail base for locking said anchor in position thereon.

8. The combination with a rail and its supporting cross tie, of an anchor arranged to abut against the cross tie and having a jaw engaging the base flange of the rail, the upper member of said jaw being fillet

welded at its edges to the upper face of the rail base.

9. The combination with a rail and its supporting cross ties, of an anchor arranged to coöperate with said rail and with one only of said cross ties to prevent creeping, said anchor comprising a depending abutment arranged to engage the side face of one of said cross ties and a flange extending from the upper edge of said abutment, said flange overlapping and being fused or welded to the upper face of the rail base at a point adjacent said abutment.

10. A one-piece rail anchor formed of a short section of a flanged bar and comprising a substantially horizontally disposed flange or member arranged to overlap and be fused or welded to the upper face of the base flange of a rail, and a vertically disposed flange or member arranged to abut against the side of the tie.

11. A one-piece rail anchor formed of a short section of a flanged bar and comprising an upper, substantially horizontal flange or member arranged to overlap and be fused or welded to the upper face of the base flange of the rail, a depending flange or member arranged to abut against the side of a tie, and a brace extending rearwardly from said tie-abutting flange and arranged to engage the lower face of the rail base.

WILLIAM M. MITCHELL
